UNITED STATES PATENT OFFICE

2,445,619

RISER

John J. Josephs, Philadelphia, Pa.

Application March 30, 1945, Serial No. 585,708

7 Claims. (Cl. 5—92)

1

My invention relates to risers used by a patient during the particular stage of convalescence when the doctor usually orders a wheel chair.

The main purpose of my invention is to provide an assembly or portable device capable for use for medical or surgical cases, war or civilian, adequately to adjust patients to changes of posture and help them to recover balance and strengthen their muscles. The device can be used by the patient without assistance, is simple to operate, positive in action, requires no adjustment, does not get out of order and with ordinary care will last indefinitely when used by patients who have been confined to bed.

My device is suitable for use in cases of infectious disease such as infantile paralysis, and in cases of malignant disease, post-operative cases, etc. Its use is highly beneficial in rehabilitation prior to occupational and recreational therapy.

A further purpose is to assist a patient first to attain a sitting position on the side of a bed, and after he or she gains sufficient strength, to help the patient to shift from a sitting position to a standing position and from a standing position to a stepping position and later a walking position.

A further purpose is to provide a portable device which may be used by a patient who is weakened by reason of confinement in bed, to aid the patient in gradually attaining a sitting position upon a bed while protecting the patient from falling forward or backward.

An additional purpose is to provide a device which may be placed alongside of a bed, by which device a convalescent may support himself upon the side of the bed in a sitting position, both legs extended, and feet resting upon a platform above the floor and at the proper relation of bed edge seat to the platform.

A further purpose is to provide a rectangular frame of the character described open at one side and enclosed at the other three sides, with a gate guard and rails in one of the enclosed sides and with steps below the gate, the first opening providing an entrance for a patient and the gate providing an exit for the patient.

A further purpose is to provide a front safety-strap and back belt, said strap and belt connected by easily opened releasable fastenings to eyes fixed on frame posts, so as to support the user sitting upon a bed.

A further purpose is to provide a portable device which may be placed between two beds, as the beds are arranged in hospitals or institutions.

2

whereby a patient from either one of the beds alongside of the device may use the same without assistance from a nurse or attendant.

Further purposes will appear in the specifications and in the claims.

Referring to the drawings, Figure 1 is an enlarged perspective view of my riser in position of use alongside of a bed.

Figure 1a is a view similar to Figure 1, but showing a modification.

Figure 2 is a perspective of my device alongside of a bed and showing the figure of a patient reclining in bed.

Figure 3 is a view similar to Figure 2, but with the patient sitting on the side of the bed with his back supported and feet resting on the chassis platform in a normal sitting position and with a safety-strap fastened across the patient's abdomen.

Figure 4 is a perspective view of a patient standing upon the platform of my riser.

Figure 5 is a perspective view of the patient learning to move feet alternately, raising, and lowering his feet and studying the difficult task of walking down steps, regaining the sense of balance.

Figure 6 is a view of the ambulatory patient walking with canes from the portable device.

Figure 7 is a view of the completely recovered patient walking from the device.

Figure 8 is a perspective view of a modification of the riser intended for use by patients from either of different beds.

Much can be done to correct defects, particularly from the deformities which often follow certain disease or casualties, if brought to the attention of a skilled physician soon enough. But correction also requires great persistence and cooperation on the part of physician, nurse, and

physical therapist, just as well as the patient, in training the convalescent through various approved methods to restore the muscle balance and make normal activity possible, before the patient can become a useful member in the community.

In many cases of paralysis there is a specific stage of recovery before the patient is able to sit up, stand on his own legs, or move around, that has not been taken care of properly by any mechanical device.

My riser responds to an increasing need for such a device which can be used by the patient, either without any help or without skilled help, and which provides adequate rehabilitation, occupational, and recreational opportunities for sick and wounded in proper sequel.

With the shortage in manpower my device fills an existing and increasing need.

My invention is of benefit first in steadying a patient when he attempts to sit up at the side of the bed and offering him a rest for his feet when he hangs his legs over the edge of the bed. It gives him support front and back in his sitting position, preventing him from falling in either direction, and offers him hand holds by which he can lift himself to standing position. The back belt and safety strap are readily placed and easily adjusted. The different positions are attained gradually and assuredly and the patient gains confidence in himself and in his ability to help himself.

The hand rails at right and left permit him to gradually raise or pull himself up into a standing position and furthermore to maneuver from one position to another in the device.

I have preferred to illustrate my invention by a single form of structure of standard steel tubing or other suitable material.

In Figure 1 my riser 10 comprises four vertical posts 11, 12, 13 and 14. The vertical posts 11 and 12 are bent or joined laterally at 15 and 16 and are connected by a continued bend, or joined at 17 beneath the bed, to prevent tipping of the frame producing a foot under the user.

The vertical posts 13 and 14 are connected at 18 by a laterally continued rail frame. Front and rear top rails 19 and 20 are provided, of which 20 connects with the vertical posts 12 and 14 at the side of the riser. A rear center rail 41 connects the vertical uprights 13 and 14 above. Platform 22 is roughened to prevent slip. Stretchers 23 extend between the respective vertical posts 11 and 13 and 12 and 14 for added strength.

Between the uprights 11 and 12 and at a position which would correspond with the height below that of a mattress or hospital bed, I provide a side top rail 24.

The horizontal top rail 19 is provided between the posts 11 and 13 to allow for hand engagement by the patient when he wishes to rise from a sitting position upon the edge of the bed to a standing position on the riser.

I also provide a back rest 25 detachable of non-stretchable but flexible webbing or canvas or suitable material that is not easily injured by heat, cold, steam or body acid fumes. It is secured at 26 and 26' to stainless clips or snap-hooks on the vertical posts 11 and 12.

An additional body supporting frontal safety-strap is illustrated in dot and dash at 27. This strap is also detachable and is secured with stainless clips or snap-hooks to eyes at 26 and 26'. The horizontal hand rail 19 is preferably bent or joined downward at 28 and 29 and then laterally at 30 in the same direction as the bar 19 to form a gate stile 31.

The construction of the tubing as just described, provides a gate 31 hinged at 32 and 33 to the posts 11. The gate also carries a latch or bolt 34, which fits in a keeper 35 in the post 13. The platform 22 is preferably welded or bolted or suitably adjusted or fixed to the vertical frame structure, its front 38 being placed above a step assembly that can be attached permanently or temporarily as at 37. This step assembly has stringers 38 and 39 fixed to the posts 11 and 13 and with a non-slipping tread 40 attached to the stringers 38 and 39 side-top-rail 41 and side-intermediate-rail 42 and bottom stretcher 18 are connected with rear-post 14 and front-gate post 13.

In Figure 8 I have shown a riser adapted for use by patients of either one or two beds. In this form the bottom stretcher is continued from each of the post members to sturdily rest upon the floor or upon chair glides if needed. The member 24 provides a first connection, the members 19 and 20 provide other connections, and the member 25 provides a further detachable connection among the respective uprights as shown in Figure 8. It will be noted that one of the top-side-rails in this form is omitted, and the eyes 26² and 26³ for a strap 25 on the vertical posts 13 and 14 have been added, also a back rest 25 and strap 27 is needed.

In Figure 1^a I have shown a variation of the structure in Figure 1. In Figure 1^a the exit is opposite the bed entrance as is the step. In other words, the entrance to and exit from my riser is on a straight line of travel, whereas in Figure 1 the patient is required to turn his body at right angles to make the exit.

I have found the structure of Figures 1 and 8 to be desirable for hospital use because beds in hospitals and other institutions are arranged in rows. A riser of the forms of Figures 1 and 8 can be conveniently placed between beds, whereas in Figures 1^a I find that this form lends itself to use in private homes where space is not at a premium because the patient can work himself out of bed into the riser and out of the riser into the room on a direct line, as in Figure 1^a, or by means of a side exit.

It will be evident that my invention offers not only mechanism by which a patient can help himself to practice sitting, standing and walking, but that because the patient is able to help himself it has a psychological effect upon the patient giving renewed confidence, cultivating balance and orientation and helping in the patient's physical development.

In view of my invention and disclosure variations and modifications to meet individual whim or particular need will doubtless become evident to others skilled in the art, to obtain all or part of the benefits of my invention without copying the structure shown, and I, therefore claim all such insofar as they fall within the reasonable spirit and scope of my claims.

Having thus described my invention what I claim as new and desire to secure by Letters Patent is:

1. In a device for assisting a convalescent patient to develop the strength to rise from bed and walk, a frame having a horizontal platform at its lower portion and above the bottom thereof, vertical standards extending upwardly from the edges of the platform so that the platform is available as a floor at the base of the standards, horizontal hand grips extending at the top of the frame between cooperating standards, a bar connecting two vertical standards transverse to the hand grips and below the hand grips and located at one edge of the frame, and a removable back rest from one vertical standard to the other at the opposite ends of the hand grips, the frame being adapted to be placed adjacent a hospital bed with the horizontal platform below the level of the mattress of the bed, with the vertical standards extending upwardly above the bed surface with the horizontal grips extending away from the bed, with the bar below the level of the mattress and close to the bed and with the back rest above the surface of the mattress.

2. In a riser adapted to assist a bedridden patient in gaining the strength to rise from bed

in one step of convalescence, a vertical rectangular frame having spaced uprights which provide access to the interior of the frame at one side, a connection between the uprights, a horizontal platform adjoining the uprights and covering the interior space within the frame, hand holds extending generally parallel on either side of the frame at the sides of the entrance, a back rest secured to the frame at the entrance and a front strap also secured to the frame at the entrance, the frame being adapted to extend vertically close to a bed and above its surface with the entrance adjoining the bed, with the connection below the bed level, with the platform below the level of the mattress and within reach of the feet of the patient, with the hand holds extending in a direction away from the bed and with the back rest and front strap adapted to fit respectively back of and in front of the patient as he sits on the bed to hold the patient against falling for a period before he rises.

3. In a device for assisting patients during convalescence, a base including a platform, apparatus including corner uprights extending from the base to make a vertically extending rectangular framework whose entire lower portion is covered by the platform, means connecting the uprights along one side, the uprights along that side above said means being free from fixed connection, bars extending transverse to the connecting means along the top of the frame forming hand holds, a back support for the patient secured to the uprights, a gate at the side of the space above the platform and steps from the platform providing for emergence of the patient, the device being adapted to stand at the side of a bed with the uprights extending along the side of the bed and at a distance away from the bed, with the means connecting the uprights resting at the side of the bed below the bed level, with the uprights along the side of the bed being free from fixed connection above the bed parallel with the bed, with the bars extending away from the bed, and with the back support secured to the uprights between the bed level and the top of the uprights at the side of the bed.

4. A riser for assisting a recuperating patient, comprising a frame open on one side above a certain level and having hand rails at the top of the frame, the frame being generally rectangular in horizontal cross section, a platform extending over the entire bottom of the frame, a door from the side of the frame permitting outlet at the side of the frame and steps connecting with the platform to permit egress, the riser being adapted to be placed against the side of a bed, open on the side toward the bed above the bed and with the steps permitting egress parallel to the length of the bed.

5. A riser for assisting a recuperating patient to resume walking after lying in bed, comprising a frame open on one side at the upper portion and having hand rails at the top of the frame, the frame being generally rectangular in horizontal cross section, a platform extending over the en-

tire bottom of the frame, a door on the side of the frame permitting outlet and steps leading from the platform at the door, the frame being adapted to be placed against the side of the bed, with the opening toward the bed and above the bed, and with the door permitting outlet at the side of the frame parallel to the length of the bed.

6. In a riser for convalescents, a rectangular frame comprising four vertical standards, a base fixed to the lower part of the standards and forming a platform above the bottom of the frame covering the entire space within the four vertical standards, a first connection between two of the standards at one side, other connections forming hand rails running transversely to the first connection and located at the tops of the standards, one hand rail connection being detachable to form a side exit, and a further detachable connection between the standards at the opposite side of the frame from the first connection, the frame being adapted to stand at the side of a bed with the first connection below the normal height of the mattress of the bed, with the hand rails extending transversely of the length of the bed, with the side exit in the direction of the length of the bed and with the further detachable connection between the standards farthest from the bed or between those nearest to the bed.
7. A riser for convalescents comprising a rectangular frame including four vertical standards at the corners of the riser and arranged in pairs, a platform connecting the standards located above the bottom of the frame and extending fully over the space inside the standards, and parallel connections between opposite pairs of standards at the tops thereof, a gate in closed position extending across from a standard at one end of the parallel connections to a standard at the other end and steps down from the platform beneath the gate, the frame being adapted to stand between two parallel beds with two of the standards adjacent one bed and two of the standards adjacent the other bed, with the parallel connections extending transversely of the lengths of the beds and the gate extending from a standard adjacent one bed to a corresponding standard adjacent the other bed.
